UNITED STATES PATENT OFFICE

2,155,773

STRAP HOLDING AND GUIDING CLIP

Howard C. Porter, Chicago, Ill., assignor to Sig-
node Steel Strapping Company, Chicago, Ill., a
corporation of Delaware

Original application August 4, 1936, Serial No.
94,199. Divided and this application November
22, 1937, Serial No. 175,793

5 Claims. (Cl. 188—83)

My invention relates to strap holding and guid-
ing clips.

It will be illustrated and described as embodied
in a clip particularly adapted to hold, feed and re-
5 tain metallic package-binder strap.

One of the objects of my invention is to pro-
vide an improved clip which will serve as a re-
taining guide through which strap may be fed
from a reel-drum.

10 Another object is to provide a clip which will
serve effectively to prevent overfeed of the strap
and yet will not unduly retard the withdrawal
of strap even though the strap may be pulled
from the coil at a considerable angle from the
15 plane of the coil.

Another object is to provide a clip which is
simple, reliable and effective.

A further object is to provide a clip which will
20 accommodate the reversely applied end of the
strap so as to hold the end, without exposure of
the sharp edges, in a position readily accessible
to the operator.

Other objects and advantages will hereinafter
25 appear.

25 In the drawing:

Fig. 1 shows the clip applied to the tubular
handle of a portable package-binder strap reel.

Fig. 2 is an enlarged vertical section of the
30 reel-handle with my improved clip applied
thereto;

Fig. 3 shows the reel-handle and clip in end ele-
vation, and

Fig. 4 is an enlarged vertical section of the clip,
35 on the line 4—4 of Fig. 3.

This application is a division of my copending
application Serial No. 94,199 filed August 4, 1936.

In general, my improved clip comprises a plate
which is rotatably and slidably held in place up-
40 on and yieldingly biased toward a support, such
as the handle of the strap-reel, and between
which and the support the strap is fed, the fric-
tion between the strap and the plate and support
serving to retard the movement of the strap there-
between.

45 In Fig. 1 the clip is shown mounted upon the
cross piece 10 of the cylindrical tubular handle
of a portable reel particularly adapted for dis-
pensing package-binder strap. Thus, in this
50 instance, the handle cross piece constitutes a
cylindrical support for and one of the strap en-
gaging elements of the holding and guiding clip.

In addition to its support the clip includes a
substantially flat plate which, with the support,
55 forms a passageway through which the strap is
fed. This plate is capable of three movements rel-

ative to its companion strap-engaging member
(i. e., the cylindrical support) viz., a rotary move-
ment and an axial movement for adjusting to the
direction of pull upon the fed end of the strap
and a radial movement effecting variations in 5
the separation (i. e., the passageway) between
them. Preferably the clip is made from a single
piece of sheet metal in the form of a U-shaped
stirrup 11 having two parallel flanges 12 and 13
and an inter-connecting yoke 14. The yoke or 10
plate 14 and support 10 form a passageway
through which the strap may be fed between the
lateral guides provided by flanges 12 and 13.
Flanges 12 and 13 are perforated by axially aligned
circular holes which are larger than the handle 15
cross piece 10 so as to fit rather loosely there-
about. A light coil spring 15 has its opposite ends
anchored to the stirrup flanges 12 and 13 by rivets
16, or other appropriate means, well above the
center of the handle cross piece 10, and bears 20
against the handle cross piece or support normal-
ly to yieldingly bias the stirrup so that the plate
14 tends to move toward—preferably to con-
tact—the cylindrical handle cross piece or sup-
port. The clip stirrup may, however, because of 25
the loose fit of the support through the holes of
flanges 12 and 13, be moved in the opposite di-
rection against the tension of spring 15 so that
the free end 20 of the strap from the coil on the
reel-drum may be inserted through the passage 30
and guideway provided by the support and the
stirrup flanges and yoke.

Thus, as the strap is pulled from the coil by
the operator it is resiliently gripped between the
stirrup yoke or clip plate and the cross piece sup- 35
port and firmly yet yieldingly retained in place
and movement of the strap through the clip
guideway is frictionally retarded. However, in the
event the strap is removed by a pull which is
largely upward, the clip can be moved against its 40
spring tension only to the extent permitted by
the looseness of the fit between the holes through
the flanges thereof and the support. In this way
the clip spring is protected against undue strain
and the clip cannot be displaced. The stirrup 45
may be rotated axially of the cross piece support
and moved longitudinally therealong automatic-
ally to adjust itself to facilitate the proper feed-
ing of the strap therethrough as it is pulled from
the rotatably mounted drum, or other source, by 50
the operator. When the strapping operation or
series of such operations is completed, the free
end of the strap projecting beyond the stirrup of
the clip may be turned back and inserted between
the clip yoke and the run of the strap which lies 55

2

between the yoke and the cross bar support, as clearly shown in Figs. 1, 2 and 4, so as to conceal the sharp edges and corners thereof and prevent them from injuring the person or clothes of those who may be working around the reel. The same result may be accomplished by turning the strap end back and inserting it under the run of strap and next to the cross bar support.

Thus, it will be apparent that I have provided a simple control clip and guide that applies a braking action upon movement of the strap as it passes therethrough and that automatically adjusts itself by sliding along and, if the support is cylindrical, by rotary movement relative to the support so as effectively to perform its function even though the strap is not pulled straight. It also serves to hold, with the sharp edges concealed, the end of the strap in a position readily accessible to the operator.

Having thus illustrated and described the preferred embodiment of my invention, what I claim and desire to secure by United States Letters Patent is as follows:

1. A strap holding and guiding clip comprising a cylindrical support, a substantially flat plate rotatably and slidably mounted upon the support, said support and plate forming a passageway through which the strap may be led between them, and means for yieldingly biasing the support and plate toward each other to retard the movement of the strap therebetween.

2. A strap holding and guiding clip comprising a cylindrical support, a substantially flat plate rotatably and slidably mounted upon the support to provide therewith a variable passageway for the feeding of the strap therebetween, a strap edge guide at one side of the passageway, and means yieldingly biasing the support and plate toward each other to cause the strap to be gripped therebetween to retard its movement through the passageway.

3. A strap holding and guiding clip comprising a cylindrical support; a stirrup having a yoke and two parallel flanges projecting from the end of the yoke, the flanges having holes therethrough slidably to receive the support and the support and yoke of the stirrup providing a passageway through which the strap may be led; and a spring secured at opposite ends to the flanges of the stirrup and partly encircling the support to bias the yoke of the stirrup toward the support.

4. A strap holding and guiding clip comprising an elongated support; a stirrup having two parallel flanges and a yoke interconnecting the flanges, the flanges having coaxial holes therethrough in which the support is located and the holes being larger than the support so as loosely to receive the same, the support and the flanges and yoke of the stirrup forming a passageway through which strap may be led; and a coil spring having its opposite ends anchored to the stirrup flanges and its intermediate portion partly encircling the support to bias the yoke of the stirrup toward the support and thereby yieldingly grip the strap therebetween.

5. A strap holding and guiding clip comprising a stirrup of substantially U shape and having two parallel flanges and an interconnecting yoke, the flanges having coaxial openings therethrough for the reception of a support which passes loosely through them and which, together with the yoke of the stirrup, forms a guideway for the passage of strap; and a coil spring having its opposite ends anchored to the stirrup flanges and positioned so that when the stirrup is applied to its support the support will be partly surrounded by the spring and the yoke of the stirrup will be biased toward the support.
